DEVICE FOR HANDLING TONGS IN WELL DRILLING DERRICKS

Filed Oct. 16, 1929

UNITED STATES PATENT OFFICE

CHARLES E. WILCOX, OF LONG BEACH, CALIFORNIA

DEVICE FOR HANDLING TONGS IN WELL DRILLING DERRICKS

Application filed October 16, 1929. Serial No. 399,985.

This invention relates to a tool handling device and relates more particularly to a device for handling tongs in a well drilling derrick.

During the course of drilling a well with the rotary method, the drill stem is coupled together and uncoupled many times. Heavy tongs are employed to engage coupling parts to set and break the connections. The tongs are suspended in the derrick by lines, there being one pair of tongs used to hold the drill stem against rotation and another operated to break or set the joint. The tongs that are operated or moved are usually manually returned to their normal position before being again used. As the tongs are extremely heavy it is more or less difficult to return them to their normal unactuated position.

It is a general object of the invention to provide a device for returning a pair of tongs to the unactuated position after being employed to rotate a coupling member, or the like, in a well drilling rig.

It is an other object of the invention to provide a device for returning tongs to the normal position after operation that is particularly effective and convenient to operate.

Another object of the invention is to provide a device of the character mentioned that does not occupy any space on the floor of the derrick and therefore does not interfere with the various operations of the rig.

Another object of the invention is to provide a device of the character mentioned that embodies means for setting it against operation.

Another object of the invention is to provide a device of the character mentioned that may be controlled to allow the tongs to remain at any desired position.

Another object of the invention is to provide a device for returning tongs to the unactuated position that is adapted to be mounted in a derrick so as to be adjustable vertically.

Another object of the invention is to provide a tong handling device of the character mentioned that is of improved construction and is particularly simple and inexpensive of manufacture.

The various objects and features of my invention will be best and more fully understood from the following detailed description of a typical form and application of the invention, throughout which description reference is had to the accompanying drawings, in which:

Fig. 1 is a side view of a typical well drilling rig showing the device provided by the invention mounted in operating position. 55 Fig. 2 is a horizontal detailed sectional view of a portion of the derrick, being a view taken as indicated by line 2-2 on Fig. 1. Fig. 3 is an enlarged longitudinal detailed sectional view of the device, being a view taken as indicated by line 3-3 on Fig. 1. Fig. 4 is a detailed transverse sectional view taken as indicated by line 4-4 on Fig. 3. Fig. 5 is an enlarged detailed transverse sectional view taken as indicated by line 5-5 on Fig. 3 60 65 and Fig. 6 is an enlarged detailed transverse sectional view taken on line 6-6 on Fig. 3. 70

The portion of the well drilling rig illustrated in the drawings includes, generally, a derrick 10 having corner posts 11 and spaced 75 horizontal girders 12 extending between the posts 11, a derrick floor 13, a rotary table 14 at the center of the derrick floor 13, and other parts commonly found in well drilling rigs. I have illustrated a drilling string 15 80 extending through the rotary table and into the derrick. The portion of the drilling string illustrated is composed of two lengths of pipe joined together by a tool joint 16. The lower section of the tool joint 16 is 85 gripped by a pair of tongs 17 suspended by a line or cable from an elevated part of the derrick and held against rotative movement by a line 18 attached to the handle of the tongs and secured to a stationary part of the derrick. A second tongs 20 is suspended from the derrick by a cable 21 and is shown in gripping engagement with the upper section of the tool joint 16. The tongs 20 is adapted 90 to be operated by a line to rotate the upper section of the joint to either set or loosen the connection. The line (not shown) for operating the tongs 20 may be operated in the usual manner by a joint breaker, cat head, or the like.

The present invention is concerned primarily with a device for returning tongs to the unactuated position after being employed to rotate a part such as a pipe, coupling, tool joint section, etc. In the following disclosure I will describe the invention as used in connection with the tongs 20, and employed principally to return the tongs 20 to their normal unactuated position. It is to be understood, however, that the invention is not to be construed as limited to the particular application or form about to be described, but is to be taken as including, any features or modifications that may fall within the scope of the claims.

The device provided by the present invention includes, generally, a body 22, a line 23 to be attached to the tongs 20 and extending into the body 22, means 24 within the body 20 for operating the line 23 to shift the tongs to their normal position adjacent the body 22, latch means 25 for holding the means 24 against operation, and means 26 for setting the line 23 against movement relative to the body.

The body 22 of the device carries the other parts and is intended to be arranged in the derrick 10. The body 22 includes an elongate tubular part 27 to be arranged substantially vertically and a sheave housing 28 at the lower end of the tubular part. The tubular part 27 may be a length of pipe, or the like, and is preferably comparatively long. The part 27 may be arranged in any suitable manner in the derrick and is preferably arranged so that the housing 28 at its lower end is at a convenient height for the operators. In the drawings I have shown the tubular part arranged between the horizontally spaced girders 12 of the derrick. In the particular case illustrated in the drawings the part 27 extends vertically between the spaced girders 12 of two vertically spaced pairs of girders. The tubular part 27 may fit between the horizontally spaced girders of each pair of girders and may be held against lateral or horizontal movement by bolts 27^a extending horizontally between the spaced girders at opposite sides of the part 27. A tubular fitting or reducer 29 may be threaded on the upper end of the part 27 and an eye bolt 30 may be threaded into the upper end of the reducer. In the preferred form of the invention the body 22 is suspended from an elevated part of the derrick by means of a chain 31 attached to the eye bolt 30 and provided with a hook 32 at its upper end. The hook 32 may be arranged over a girder or girders of the derrick and may extend through a link of the chain 31. The hook may be arranged through various links of the chain to vary the height or position of the body 22.

The sheave housing 28 is carried at the lower end of the tubular part 27 and is provided to carry a sheave 33. The housing 28 may

have a substantially disc shaped hollow central portion having spaced side walls 34. An upwardly extending tubular projection 35 is provided on the housing and is screw threaded on the lower end of the tubular part 27. The projection 35 is at one side or edge of the housing so that the central portion of the housing is offset from the tubular part 27 and is carried so that the side walls 34 extend parallel with the tubular part 27. The sheave 33 is rotatably mounted between side walls 34 on a shaft or pin 36. The sheave 33 is mounted to rotate about a transverse or horizontal axis and is located so that its periphery is substantially in alignment with the central longitudinal axis of the tubular part 27. The periphery of the sheave 33 is preferably provided with a groove 40 to carry the line 23. An opening 41 is provided in the housing to allow for the insertion of the sheave. An opening 42 is provided in the housing 28 to pass the line 23 into the body. The opening 42 is positioned so that the line 23 extends horizontally into the housing 28 and operates in the groove 40 of the sheave. In accordance with the present form of the invention a tubular projection or extension 43 extends outwardly from around the opening 42.

The line 23 may be any suitable form of flexible element, for example it may be a cable, chain, or like flexible part. In the present case, the line 23 may be considered a stranded cable. The line 23 is preferably somewhat longer than the tubular part and may be any suitable length, depending upon the positioning of the device relative to the tool to be operated. The line 23 may be provided at its end with suitable means for attachment to a pair of tongs, or other tool.

The means 24, normally yielding, draws or urges the tongs 20, attached to the line 23, toward the body 22. The means 24 is in the form of spring means and includes, a stop in the form of a socket 50 applied to the end of the line 23 and slidable within the tubular part 27, and a helical spring 51 arranged under compression between the socket 50 and an annular shoulder 52 in the opening 53 of the tubular projection 35.

The socket 50 may be any suitable form of rope or cable socket and is securely attached to the end of the line 23. The socket 50 may be a tubular part having an upwardly divergent opening 54. The strands of the end portion of the line 23 may be set or retained in the socket in any suitable manner, for instance, they may be separated or frayed in the opening 54 and cast or set in babbitt, lead, or the like. The upper end of the socket 50 around the opening 54 is beveled inward and downward, as clearly illustrated in Fig. 3 of the drawings. The spring 51 is sufficiently strong to effectively move the tongs 20 toward the body. In accordance with the in-

vention a resilient bumper or stop 55 is provided in the upper end of the tubular part 27 to limit the upward movement of the socket 50. The stop 55 may be carried within the 5 reducer 29 and may extend into the part 27. The stop 55 may be retained in position by a key or pin 56 extending transversely through the reducer and stop.

The latch means 25 for holding the actuating means 24 against operation is provided 10 to hold the means 24 against operation when the line is extended so that the tongs 20 may be freely operated. The means 25 includes a latch 60 carried on a pivot bolt 58 and is 15 arranged between flanges 59 of brackets 57 so that it is held against displacement.

The latch 60 is mounted to pivot about an axis transverse of the longitudinal axis of the tubular part 27 and has a head portion 61 20 at its upper end. The head is provided with a bill or lug 62 which is adapted to extend through an opening 63 in the side walls of the tubular part 27 and which has an upwardly and outwardly tapered face 64 at its 25 inner end adapted to engage the beveled upper end of the socket 50. The face 64 is inclined so as to evenly seat on the upper end of the socket.

The lower portion of the latch 60 is in the 30 form of a lever or handle 65. The handle 65 extends downwardly and outwardly from the pivotal connection of the latch and is provided with an opening 66 adjacent its lower end to receive an operating line or rope. The 35 latch 60 is normally held in a position where the lug 62 is free of the opening 63 by a spring 67. In the preferred form of the invention the spring 67 is in the nature of a U-shaped leaf spring. The spring 67 has one of its 40 arms secured to the inner side or edge of the head 61 and its other arm in pressure engagement with the exterior of the tubular part 27. In the construction described above, the face 64 and the upper end of the socket 45 50 are formed so as to lock together and resist the action of the spring 67 when the latch is in the set position, such as illustrated in Fig. 3 of the drawings.

The means 26 for setting the line 23 against 50 movement relative to the body 22 may be in the nature of any suitable form of cable clamp carried by the body to engage the line 23. In the preferred form of the invention the means 26 includes a pivotally mounted clamp 55 70 mounted in the extension 43 to engage the line 23 in the opening 42. The clamp 70 is mounted in a transverse opening in the extension 43 on a pivot pin 71. A cam part 73 is provided on the inner end of the clamp and is adapted to force the line 23 against the opposite wall of the opening 42. The wall of the opening 42 opposite the clamp 70 may be provided with a recess 74 into which the cam part 73 is adapted to force the line 23. 65 A handle 75 is provided on the clamp 70.

In using the device provided by this invention, the parts are initially arranged as shown in Fig. 1 of the drawings. In this position the latch 60 is released and the clamp 70 may either be set or released, depending 70 upon the length of the line 23 and the relative positions of the handle of the tongs 20 and the body 22 of the device. When the tongs 20 are to be operated the clamp 70 is released if it had been set. Upon the tongs 75 20 being operated, the line 23 is operated and the socket 50 is moved downward to the lower portion of the tubular part 27, say, to a position such as illustrated in Fig. 3. If desired, the latch 60 may be operated so that 80 the face 64 seats against the upper end of the socket and the socket is held against upward movement. Upon the cat head line or the joint breaker being released, the latch 60 may be released and the spring 67 will 85 operate to move the socket to the upper end of the tubular part 27 and the tongs 20 will be returned to a position adjacent the device. It will be obvious that the clamp 70 may be operated to prevent movement of the line 90 23 whenever desired.

Having described only a typical preferred form of my invention, I do not wish to limit myself to the specific details set forth, but wish to reserve to myself any changes or 95 variations that may appear to those skilled in the art or fall within the scope of the following claims:

Having described my invention, I claim:

1. A device of the character described including, a body, a line adapted to be attached to a tool, means acting through the line for yieldingly urging a tool toward the body, and means for holding the first-mentioned means against operation.

2. A device of the character described including, a body, a line adapted to be attached to a tool, means acting through the line for yieldingly urging a tool toward the body, and latch means for preventing operation of the line.

3. A device of the character described including, a body, a line adapted to be attached to a tool, means acting through the line for yieldingly urging a tool toward the body, and clamp means for preventing operation of the line.

4. A device of the character described including, a body, a line adapted to be attached to a tool, means acting through the line for yieldingly urging a tool toward the body, and means for holding the first-mentioned means against operation when the line is in an extended position.

5. A device of the character described including, a body, a line adapted to be attached to a tool, means acting through the line for yieldingly urging a tool toward the body and latch means for holding the first-men-
